UNITED STATES PATENT OFFICE

LOUIS SCHNEER, OF WATERBURY, CONNECTICUT

CAP FOR PASTE TUBES

Application filed May 25, 1931. Serial No. 539,784.

This invention relates to collapsible paste tubes, and more particularly to a rotatable cap adapted to be permanently attached to the discharge outlet neck of said tube.

One object of the present invention is to provide a paste tube cap of the above nature which will be limited in its sliding motion in both directions.

A further object is to provide a device of the above nature which will cut off the ribbon of extruded material cleanly and sharply without the necessity of wiping the tube upon a brush.

A further object is to provide a device of the above nature which will be simple in construction, inexpensive to manufacture, easy to install and manipulate, compact, ornamental in appearance, and very efficient and durable in use.

With these and other objects in view, there have been illustrated on the accompanying drawing three forms in which the invention may be conveniently embodied in practice.

In the drawing:

Fig. 1 represents a side elevation of a paste tube with the improved cap permanently attached thereto.

Fig. 2 is an enlarged fragmentary side elevation of the same shown partly in section.

Fig. 3 is a transverse sectional view of the same taken along the broken line 3—3 of Fig. 2, looking downwardly, with the cap in open position.

Fig. 4 is a fragmentary view in elevation of the upper part of a tube having a modified form of cap attached thereto.

Fig. 5 is a perspective view of the cap shown in Fig. 4, illustrating the interior construction thereof.

Fig. 6 is an enlarged fragmentary view in elevation of another modified form of cap and the upper part of the paste tube to which it is attached.

Fig. 7 is a transverse sectional view of the same taken along the line 7—7 of Fig. 6, the cap being in open position.

Referring now to the drawing in which like reference numerals denote corresponding parts throughout the several views, the numeral 10 indicates a paste tube of the usual

construction having one end flattened and provided with a closure clip 11, the other end of the tube having a conical shoulder 12 terminating in an open discharge neck 13 through which the paste is adapted to be extruded.

In the first form of the invention shown in Figs. 1, 2 and 3, the neck 13 is provided adjacent its top edge with a vertical orifice 14 of rectangular shape below and to one side of which is a horizontal elongated lug 15 for a purpose explained below.

In order to close the open neck 13 and prevent the discharge of paste through the orifice 14 until desired, provision is made of a cylindrical cap 16 having a hexagonal head 17 for convenience in manipulation, said cap being preferably formed of plated brass or any other suitable rustproof material. The cap 16 is provided with a rectangular vertical slot 18 having the same size as the slot 14 and adapted to be brought into alignment therewith when the cap is twisted in a counter-clockwise direction as far as it will go. The twisting motion of the cap in both directions is limited by a horizontal rectangular slot 19 within which fits the lug 15, as clearly shown in Figs. 1 and 2.

To permanently lock the cap 16 upon the neck 13 of the tube 10, the slot 19 has a vertical side slot 20 extending down through the lower edge of said cap. A reduced tongue section 21 extends from one side of said side slot 20 and is adapted to be inserted through a rectangular eye 22 adjacent the other side of said slot 20. The tongue 21 is then bent backwardly upon itself, as clearly shown in Figs. 1, 2 and 3, thereby securely locking the cap 16 in position.

In the modified form of the invention shown in Figs. 4 and 5, a cap 23 is disclosed which is similar to the first form of cap, except that instead of having a tongue and eye locking connection at the bottom, a resilient tongue 24 is provided below the horizontal slot 19. The tongue 24 has a beveled recess 25 on its inner surface for permitting the cap to be readily assembled upon the neck of the tube by the simple operation of sliding said cap longitudinally upon the neck 100

with the nib 15 in alinement with said recess 25. This will cause the resilient tongue 24 to yield outwardly and snap back underneath the nib in the position shown in Fig. 4. The 5 free end of the tongue 24 is provided with a reduced finger 26 and has an inclined section 27 whereby there will be no danger of breaking off said tongue when the cap is pulled upwardly. This form of cap will preferably be made of some strong rustproof material, such as celluloid or plated metal.

In the modified form of the invention shown in Figs. 6 and 7, the orifices 28 and 28a in the cap and neck are made oval shaped, 15 and the base of the cap below the locking slot 19 is initially provided with an outwardly extending loop 29 shaped as shown in dotted lines in Fig. 7. This loop will permit the cap to be assembled upon the neck by pushing it downwardly in such a manner that the loop 29 passes over the nib 15. After the loop 29 has passed beneath the nib 15, said loop may be bent over laterally into flat contact with the cap by means of a pair of pliers 20 or any other suitable tool into the position shown in full lines by the numeral 29a in Fig. 7.

Operation

30 In the operation of each of the three forms of the invention, when it is desired to extrude the contents of the paste tube, it will only be necessary to turn the cap 16 in a counter-clockwise direction as far as it will go. The orifice of the cap will then be in alinement with the orifice of the tube neck 13. The operator will then press upon the tube 10 causing paste to flow out through the neck and cap to the form of a ribbon which may be received on 35 a tooth brush or any other implement. The ribbon of paste may then be sheared off in a clean cut manner by twisting the cap in the reverse direction as far as it will go.

If desired, the side of the cap containing 45 the discharge orifice may be made relatively thin so as to obtain a knife edge cutting action when the tube is being closed, thus preventing any substantial amount of paste remaining on the outside of the neck.

50 While there have been disclosed in this specification three forms in which the invention may be embodied, it is to be understood that these forms are shown for the purpose of illustration only, and that the invention is 55 not to be limited to the specific disclosures but may be modified and embodied in various other forms without departing from its spirit. In short, the invention includes all the modifications and embodiments coming within the 60 scope of the following claims.

Having thus fully described the invention, what is claimed as new, and for which it is desired to secure Letters Patent, is:

1. In an attachment for the neck of a paste 65 tube having an outstanding lug in the side

thereof, a rotary cap for fitting over said neck, said cap having a transverse slot for fitting over said lug to limit the twisting of said cap and to lock it on said neck, and a flexible tongue below said slot capable of yielding outwardly upon engaging said lug to permit the fitting of said cap over said neck.

2. In an attachment for the neck of a paste tube having an outstanding lug in the side thereof, a rotary cap for fitting over said neck, said cap having a transverse slot for fitting over said lug to limit the twisting of said cap and to lock it on said neck, and a flexible tongue below said slot capable of yielding outwardly upon engaging said lug to permit the fitting of said cap over said neck, said tongue having a beveled recess for engagement with said lug.

In testimony whereof, I have affixed my signature to this specification.

LOUIS SCHNEER.
